Primary Examiner — Antoine D Davis(74) Attorney, Agent, or Firm — David A. Burge(57) CLAIM

I claim the ornamental design for mason's guide line holders or similar articles, as shown and described.

DESCRIPTION

FIG. 1 is a perspective view of my new invention showing mainly top, left side and forward end features thereof;

FIG. 2 is a top view thereof;

FIG. 3 is a left side view thereof, it being understood that a right side view would be a mirror image reversal hereof;

FIG. 4 is a rearward end view thereof on an enlarged scale; and,

FIG. 5 is a forward end view thereof on the same enlarged scale as FIG. 4.
